INVENTOR.
CHARLES G. TIEFEL
BY *Ed. Tiefel*
ATTORNEY

UNITED STATES PATENT OFFICE.

CHARLES G. TIEFEL, OF ROCHESTER, NEW YORK, ASSIGNOR TO TODD PROTECTOGRAPH COMPANY, INC., OF ROCHESTER, NEW YORK.

CHECK WRITER.

Application filed March 18, 1921. Serial No. 453,290.

To all whom it may concern:

Be it known that I, CHARLES G. TIEFEL, citizen of the United States, residing at Rochester, in the county of Monroe and 5 State of New York, have invented certain new and useful Improvements in Check Writers, of which the following is a specification.

This invention relates generally to printing machines, and has particular reference to machines used for printing limiting inscriptions upon bank checks or other valuable instruments.

In the accompanying drawings the improvements are shown embodied in a machine of the type fully shown and described in U. S. Letters Patent No. 1,138,330, issued May 4, 1915, to Libanus M. Todd and Charles G. Tiefel. One trouble users have 10 experienced with such machines is that occasionally the operator's attention may be distracted while writing the amount upon a check, and he cannot remember just where he left off. He must then examine the 15 check to see how much of the amount has been printed, or if he thinks he remembers where he left off he may be mistaken, and as a result may repeat the last word printed and thereby spoil the check. As checks are 20 usually serially numbered and must usually all be accounted for in some way, a spoiled check is a source of some trouble and annoyance. One object of the present invention is to provide a mechanism which will 25 indicate to the operator whether the last impression intended to be made has actually been made, and prevent him from erroneously repeating an impression and thereby spoiling the check. Some such mechanism 30 is particularly desirable in machines constructed to disrupt the fibres of the paper as an incident to printing, as such machines incorporate the printing ink with the fibres of the paper to such a degree that it is practically impossible to make an erasure preparatory to printing the correct matter.

Another object of the invention is to provide an improved construction of the co-operating impression faces of the type and platen whereby the fibre disrupting function will be performed in a very effective way without at the same time materially weakening the paper.

With these and incidental objects in view 55 the invention consists in certain novel fea-

tures of construction and combinations of parts, the essential elements of which are set forth in appended claims and a preferred form of embodiment of which is herein-after described with reference to the drawings which accompany and form a part of this specification.

Of said drawings:

Fig. 1 is a longitudinal section through a machine of the Todd and Tiefel type, 65 with the present improvements applied thereto.

Fig. 2 shows on an enlarged scale the construction of the impression faces of the type.

Figs. 3 and 4 are respectively a development of and a partial section through the platen, and show the construction of the impression face of the platen.

Fig. 5 shows an enlarged scale the appearance of the printing effected by the improved construction.

Fig. 6 is a reverse view of the impression shown in Fig. 5 and shows the way the co-operating faces of the type and platen 80 act in disrupting the fibres of the paper.

Fig. 7 is a bottom view of the machine locking mechanism, with the parts in the positions they occupy just before the lock is rendered effective.

Fig. 8 is a section on the line 8—8, Fig. 1.

Fig. 9 is a section on the line 9—9, Fig. 1.

Fig. 10 is the same as Fig. 9, except that some of the parts are shown in a different position.

Fig. 11 shows some of the type selecting mechanism of the illustrative machine.

Fig. 12 is a section on the line 12—12, Fig. 1.

As is well known in the art, the Todd and Tiefel machine used for illustrative purposes has a type carrier which is adjustable to different positions to select the matter to be printed, and is then rotatable with the selected type in engagement with a rotary 100 platen to effect the printing. The adjustment of the type is effected by selective devices comprising a dial or index for guiding the operator to get the right adjustment, while the printing operation of the carrier 105 and platen is effected by means of a driving mechanism comprising an impression or operating handle. The improvement provides mechanism whereby operation of the impression handle to print a word which 110

should not be repeated sets a locking mechanism which prevents moving the handle a second time until the lock is released. This release is effected by an operation of the 5 type selecting mechanism. In other words, after the machine has been operated to print from a type form the lock is set so that another operation of the impression handle is prevented until the type carrier 10 has been given another adjustment. The operator is therefore automatically prevented from accidentally repeating an impression by an incorrect second operation 15 of the impression handle, while, at the same time, if he is in any doubt, by trying the impression handle to see if it is locked, he will be able to tell whether the last form selected has been printed from, and this in connection with a comparison of the type 20 selecting device with the matter to be printed will indicate the next step to take in completing the printing of the inscription. While, as will be clearer later on, this idea can be used to advantage in many 25 different kinds of machines, it is particularly valuable in machines which do the printing in such a way that erasures for correcting purposes cannot readily be made.

In the Todd and Tiefel machine the 30 operating impression faces of the type and platen are provided with complementary ridges and grooves which, as they mesh together with the paper between them, disrupt the fibres of the paper as an incident to 35 printing. It has been found preferable to have these ridges and grooves extend in a truly circumferential direction, or parallel to the planes of rotation of the type carrier and platen. As the lengths of the ridges on 40 the type are limited only by the widths of the type faces, however, this circumferential arrangement of the ridges and grooves results in the paper being disrupted, torn, or slitted in lines of appreciable length parallel to the length of the printed line, and if 45 a poor quality of paper is used it is likely to tear in handling. The likelihood of this may be lessened by having the ridges and grooves run substantially parallel to the axes. 50 of the type carrier and platen, or it may be further lessened by having the impression faces of the type and platen provided with co-operating points and sockets acting on the die and counter die principle to puncture 55 the paper instead of disrupting, tearing or slitting it in lines. Either of these constructions, however, requires gearing or other mechanism fixing a definite relation between the movements of the type carrier and platen so as to insure reasonably accurate 60 registration of the ridges and grooves or points and sockets when the type and platen come together to perform their functions. The present invention gives the advantages 65 of the modifications just mentioned, so far

as the effect upon the paper is concerned, without its being necessary to use gearing or other mechanism to maintain a definite meshing relation between the type and platen. This is accomplished by having the 70 ridges on either the type or platen unbroken or continuous with the ridges extending in a truly circumferential direction or parallel to the plane of rotation while the co-operating impression face or faces may be provided with projections, preferably of pyramidal shape, meshing with the grooves between the ridges on the opposing impression face or faces. From a manufacturing stand-point it is preferable to have the continuous 80 ridges on the type faces and the projections on the face of the platen, as the projections may readily be formed by a plurality of intersecting grooves and this grooving can be done more readily on the platen than on the 85 type faces. As before suggested, such a construction permits loosely supporting the platen on its axis without any means for controlling its circumferential position, as it will be ready to perform its function in 90 any circumferential position at which it may come to rest.

Described in detail and with reference to the drawings, the improved machine has a base 20 and a top casing 21. This top casing is hinged to the base, one of the hinges being shown at 22, Fig. 8, so that the top may be moved relative to the base to give access to the mechanism. Latches, one of which is shown at 23, Fig. 1, prevent movement of the top 21 relative to the base 20 when the machine is in use. The lower edges of the top casing are cut away, as shown at 24, to provide a slot thru which the paper to be printed upon may be inserted. A 100 hinged plate 25 closes the lower part of the hinged top 21 and serves as a guide for the paper, while a plate 26 secured to the base 20 serves as a work supporting table. The plates 25 and 26 are provided with suitable 105 openings thru which a platen 27 may be raised into position to co-operate with printing type more fully referred to later on.

The platen 27 is in the form of a wheel 110 rotatably supported between the arms of a yoke 28 secured to a rock shaft 29 journaled in ribs 30 across the base of the machine. Near one end of the shaft 29 is an arm 31 co-operating with a cam 32. For present 115 purposes the arm 31 may be considered as being rigid with the shaft 29 and the cam 32 may likewise be considered as being rigid with the shaft 33. As a matter of fact both the arm and the cam are adjustable relative to their respective shafts to regulate the impression, but the means for effecting the 120 adjustments need not be described here.

The shaft 33 just mentioned is journaled at its ends in the upper portion 21 of the 125 casing. Fastened to the shaft 33 near its 130

forward end is a gear 34 meshing with a gear 35 fastened to the inner end of a short shaft 36 journalled in a boss 37, Fig. 8, on the side of the casing. At its outer end the 5 shaft 36 is provided with an impression or printing handle 38. The gears 34 and 35 are the same size so that for each full turn of the handle the shaft 33 will also make one complete rotation.

10 The printing type previously referred to are arranged in lines as shown at 41, Fig. 1, there being one of these lines for each word or corresponding matter which the machine is intended to print. The type lines are 15 carried by a plate 42 secured to an element 43, the construction of the type plate and element 43 being such that the impression face of each type line will be concentric to the center of the shaft 33. The element 43, 20 which, by the way, is provided with end portions 44 surrounding the shaft 33, has a rib or corresponding projection 45 engaging a slot extending longitudinally of the shaft 33, thereby permitting adjustment of the 25 element 43 and type plate to different positions along the shaft, but causing them to move with the shaft when the shaft is turned.

Embracing the element 43 and type plate 30 42 attached to the element is a yoke 47 loosely supported by the shaft 33. Secured to the yoke 47 is a handle 48 provided with a pointer 49 co-operating with a dial or index 50 on the top of the machine. The 35 construction is such that when the pointer 49 is opposite one of the lines on the dial 50 the type line for printing the corresponding word will be in alinement with the platen 27. The handle 38 may then be operated to turn the shaft 33 and type carrier 40 42 to effect a rolling engagement of the selected type line and platen.

The platen 27 is normally held in the position in which it is shown in Fig. 8, but 45 just before any type line reaches the position where it should begin to co-act with the platen the platen is raised by the portion 53 of the cam 32 engaging the arm 31 and rocking the shaft 29 and platen 27 to raise 50 the platen to printing position. After the printing has been completed the platen is returned to its normal position by a spring 54.

As so far described in detail, it is apparent 55 that the printing handle 38 might be operated over and over again to print from the same type line 41. For reasons explained near the beginning of this specification, it is desirable to prevent such repeated or continuous operation of the impression handle as a means for preventing accidental repetition of a word. The mechanism for preventing two successive operations of the impression handle 38 without 60 an intervening adjustment of the type car-

rier includes a pawl 61, Figs. 7, 9 and 10, which after an operation of the printing handle will engage a shoulder on the periphery of a disc 62 rigid with the type carrying member 43 and prevent further 70 movement of the operating shaft 33. The way in which the pawl engages the shoulder on the disc is shown in the figure last mentioned. The pawl 61 is pivoted on a lever 63, which is in turn pivoted at 64 to an 75 arm 65 extending laterally from the rear end portion of the yoke 47. A pin 66 on the side of the lever 63 limits movement of the pawl 61 in one direction, while a pin 67 on the pawl limits the movement of the 80 pawl in the opposite direction.

Pivoted to a suitably formed surface on the hub of the yoke 47 is a pawl 68 connected by a spring 69 with the pin 67 on the pawl 61. The pawl 68 is provided with a 85 shoulder 71, (Fig. 7), to engage the edge of the lever 63 and hold the lever in the position in which it is shown in Fig. 9. In this position the locking pawl 61 cannot engage the shoulder on the disc 62. When 90 the impression handle 38 is operated, however, to rotate the shaft 33, a suitably shaped projection 72 on the side of the disc 62 will engage the portion 73 of the pawl 68 and rock the pawl 68 on its pivot, whereupon the spring 69 will swing the lever 63 on its pivot and bring the point of the locking pawl 61 into position to engage the shoulder on the disc 62 and arrest the 95 shaft 33.

The upper end of the lever 63 is beveled to engage V-shaped notches in a rack or cam bar 74 secured to the inner side of the casing 21. The bar 74 is shown in section in Figs. 9 and 10 and in dotted outline in Fig. 1. After the pawl 68 has been tripped by the projection 72 and the pawl 61 engaged with the shoulder on the disc 62, the 100 V-shaped upper end of the lever 63 will be seated in one of the notches in the cam bar 74.

If the type selecting handle 48 is then moved in either direction the side of the V-shaped notch in the cam bar 74 will rock the lever 63 on its pivot and withdraw the pawl 61 from engagement with the shoulder on the disc 62. As will be seen in Fig. 7, the shoulder 71 on the pawl 68 is inclined, and by the time the lever 63 has been swung as far as the inclined edge of the notch in the cam bar 74 can swing it the inclined shoulder 71 on the pawl 68 will come into play and act to swing the lever 63 a little farther so that the upper end of the lever will not touch the points on the cam bar 74 when the type carrier is shifted. The spring 69 is stiff enough to effect this camming action of the pawl 68. In order to be sure, however, that the lever 63 is swung far enough to clear the cam bar 74, the portion 115 75 of the disc 62 is graduated so that it will 120 125 130

act against the end of the pawl 61 as a cam to swing the lever 63 on its pivot in case the proper extent of movement has not already been effected by the action of the inclined 5 shoulder 71 of the pawl 68.

From the foregoing it is clear that when the shaft 33 is turned to print from the selected line the pawl 68 will be swung by the projection 72 to free the lever 63, thereby 10 allowing the lever to swing on its pivot and carry the pawl 61 into engagement with the periphery of the disc 62 so that when the shoulder on the disc engages the end of the pawl further movement of the shaft 33 will 15 be prevented. The movement of the lever 63 to carry the pawl 61 into effective position also engages the beveled upper edge of the lever 63 with the correspondingly shaped notches in the cam bar 74, and when the yoke 20 47 is shifted to select another type line for printing the cam bar 74, inclined shoulder 71 on the pawl 68, or the cam portion 75 of the disc 62 will operate to swing the lever 63 to the position shown in Fig. 9, in which 25 position the pawl 61 cannot interfere with rotation of the shaft 33. These operations of the parts are repeated at each operation of the impression handle 38 and adjustment of the type selecting mechanism so that it is 30 impossible to continue the movement of the impression handle and thereby repeat the impression of words where repetition would spoil the check.

As shown in Fig. 11, the illustrative machine is provided with a re-inking position 35 77, and a position marked "Cancel", shown as 78. The re-inking position on the dial corresponds to the groove 79, Fig. 9, in the type plate. When the machine is re-inked 40 by applying ink to rollers 81 and 82 the type selector may be set to the "re-ink" position and the handle 38 turned repeatedly to distribute the ink on the rolls and type. It would of course, be undesirable to have to 45 operate the type selector to free the lock after each rotation of the handle 38 in re-inking, and for this reason the notch in the cam bar 74 may be omitted at the "re-ink" position, as shown at 83, Fig. 1. The notch 50 corresponding to the "cancel" position may also be omitted (as shown at 84) for the same reason, because in operating the machine for cancelling a check it is customary to insert the check in the machine and write 55 the word "cancel" or "cancelled" repeatedly all the way across the face of the check. Here again it is desirable to make it unnecessary to have to shift the type selecting mechanism between each rotation of the impression handle. It is apparent, of course, 60 that while the pawl 68 is tripped at each rotation of the impression handle 38 and shaft 33, the inclined shoulder on the pawl 68 or the cam portion 75 of the disc 62 will 65 act to swing the lever 63 to the proper posi-

tion so that there will be no interference between the lever 63 and the cam bar 74 when the type carrier is shifted to a new position ready to print matter which would spoil the check if it should accidentally be repeated. 70

The improved construction of the type and platen is illustrated in Figs. 2, 3 and 4, while the effects produced by the improved construction are illustrated in Figs. 5 and 6. As shown in Fig. 2, the type faces are provided with grooves which incidentally form ridges extending all the way across the type. These ridges are arranged circumferentially of the type carrier and parallel to the plane of rotation thereof. The 80 impression face of the platen is provided with two sets of grooves, one extending circumferentially of the platen wheel and parallel to the plane of rotation of the wheel, while the grooves of the other 85 set intersect the grooves of the first set at a right angle, resulting in the formation of a multiplicity of points which are pyramidal in shape, altho the depths of the intersecting grooves may be varied so as to make the 90 tops of these projections flat or blunt if desired. The construction is such that the projections on the platen are in circumferentially extending rows meshing with the grooves in the faces of the type so that as 95 the paper is rolled between the type and platen to print, the projections on the platen will penetrate or perforate the paper as indicated in Fig. 6, instead of, as in the older machines, shredding or tearing the paper in 100 slits corresponding to the lengths of the ridges across the faces of the type. The improved construction, therefore, gives results substantially the same as the older construction, so far as solidity of outline of the matter printed is concerned, while at the same time the fact that the paper is punctured instead of torn or cut in slits leaves the paper in better shape for handling. 105

It has already been pointed out that this 110 very desirable result is obtained without providing the platen and type with co-operating points and sockets, and that by being able to get away from this point and socket construction it has been possible to avoid using 115 gears or corresponding connections for maintaining the platen 27 in a fixed relation with the type carrier 42. In other words the platen 27 may be freely spun or turned on its axis to any position without interfering with the work of the machine when it is operated to print, a thing which could not well be true if the co-operating impression faces of the type and platen were constructed 120 on the point and socket plan above mentioned. 125

In describing the construction of the machine it has been incidentally necessary to describe the operation of the various parts of the mechanism to such an extent that it is 130

thought that the statement of operation usual at this point may be omitted.

While the mechanism herein shown and described is admirably adapted to fulfill the objects primarily stated, it is not the desire to be limited to the one embodiment, as the invention is capable of embodiment in various forms and modifications all coming within the scope of the claims which follow.

10. What is claimed is:

1. In a machine of the class described, the combination with a printing couple comprising a platen and a plurality of type forms for printing characters representing various monetary values, of means for operating the printing couple to print selectively from the various forms, and mechanism controlled in turn by said means for preventing successive impressions from any one of said type forms.
15. 2. In a machine of the class described, the combination with a printing couple comprising a platen and a type carrier adjustable to bring a plurality of different type forms selectively to printing position, of means for effecting the adjustments of the type carrier, means for effecting relative printing movements of the platen and carrier, and devices operative in any selected positions of the carrier for compelling alternating operation of the type carrier adjusting means and the printing means to print an inscription requiring two or more operations of the printing means.
20. 3. In a machine of the class described, the combination with a printing couple comprising a platen and a type carrier adjustable to a plurality of different printing positions, of means comprising an operating handle for effecting a relative printing movement of the carrier and platen, mechanism rendered effective by operation of said means with the type carrier in any of said positions to prevent an immediately following printing operation with the carrier in the same position, and devices for rendering said mechanism ineffective by adjustment of the type carrier.
25. 4. In a machine of the class described, the combination with a printing couple comprising a platen and a type carrier provided with type forms for printing the various words used in expressing values, of mechanism comprising an impression handle for operating the printing couple to print from any of the forms, and devices controlled by said mechanism for locking the impression handle thereof against operation to print from any one of said type forms in succession.
30. 5. In a machine of the class described, the combination with a plurality of type forms and means for selecting the form to be printed, of mechanism for taking impressions from the selected form, locking devices for said mechanism, means for operating the locking devices by operation of said mechanism to prevent continuous operations of the mechanism to print any selected one of said type forms in succession, and devices for operating the lock by operation of the type selecting means to free the impression taking mechanism for operation.
35. 6. In a machine of the class described, the combination with a type carrier provided with a plurality of type forms and means for inking the forms, of a platen common to said forms, the impression faces of the type and platen being constructed to disrupt the fibres of the paper as an incident to the printing, devices for effecting engagement of any desired form with the platen to print from the said form, and locking mechanism controlled by said devices for preventing the impression of any one of said type forms in succession.
40. 7. In a machine of the class described, the combination with a platen, of a type carrier provided with a plurality of word type forms, the impression faces of said type forms and platen being constructed to disrupt the paper as an incident to printing, devices for inking the type, means for adjusting the type carrier to set any desired form in printing relation with the platen, impression devices for bringing the platen and the selected type form together to print, and locking devices operative with any one of said type forms in printing position and requiring alternating operation of the type carrier adjusting devices and the impression devices to print an inscription comprising two or more words.
45. 8. In a machine of the class described, the combination with a rotary platen having its impression face provided with a plurality of projections arranged in circumferential rows, of a rotary type cylinder provided with circumferentially arranged type characters adapted for rolling contact with the face of the platen, the printing faces of which type characters are provided with ridges extending circumferentially of the carrier, said ridges engaging the platen between the projections thereon during the printing movement of the carrier and platen, and means for operating the carrier to print from the desired type characters.

In testimony whereof I affix my signature.

CHARLES G. TIEFEL.
